SIGNALS AND CONTROLS FOR PASSENGER
AND FREIGHT ELEVATORS AND FOR
OTHER PURPOSES

William Noble Dickinson, Rockville, Centre, N. Y.

Application June 20, 1931, Serial No. 545,759

25 Claims. (Cl. 177—336)

The desirability of my system will be described as related to a multiplicity of elevators. It provides features not heretofore available, effects a substantial saving in material and labor and involves the use of standard parts, which permits of economical and convenient manufacture and assembly.

A typical arrangement of flashlight signals as heretofore employed includes an "Up" and a "Down" push button at each intermediate landing and an "Up" and a "Down" signal lantern over the door leading to each elevator at each intermediate landing; with a single push button and a single lantern over each door at terminal landings. The elevators are solidly enclosed and the landing doors are opaque. The pressure of a landing button releases a floor contact on a master controller which is electrically connected to individual controllers. These latter are mechanically geared to each elevator and, through the medium of these, the first elevator to approach the corresponding landing in the desired direction of elevator travel causes the corresponding signal lantern to become illuminated and an operator's signal light in the corresponding car to glow.

There are a number of inadequate or undesirable features frequently encountered in installations of these types.

With my invention, the intending passenger, on pressing a button, receives instant visual notification as to whether or not his call has been registered and of the cancelling of this registration when such occurs. Also, without moving from his position or turning his head, he is furnished with both audible and visual indication of the approach of the serving elevator, and audible and visual indication as to whether it is to the left or to the right of the push button, or across the hall, and the individual elevator is identified. One elevator, only, signals a landing in either direction at one time. One controller, only, is required and it may be located in a vertical or in a horizontal position or at any angle necessary to permit of its being placed within space available, and is adjustable for various conditions.

In a sixty-floor sixteen elevator installation, with one set of push buttons located midway in each bank of eight elevators on opposite sides of a landing, about seventy-five percent of the electric lamps and conductor length are eliminated.

In general, my controller includes one traveling magnet or solenoid corresponding with each elevator, and two separately mounted cross-arms (one for up and one for down), corresponding

with each floor. Each cross-arm contains a projection or contacting finger corresponding with each elevator. Each traveling solenoid is geared to the mechanism of its elevator and each cross-arm is pivoted on stationary supports and sets at right angles to the paths of the solenoids. Provision is thus made for electrically relating any elevator to any floor for either direction of elevator travel.

At the landings, each push button is provided with a transparent or translucent face, an electric globe, reflectors, an electro-magnet and a polarized magnet, which latter operates light baffles and audible signals. Certain sections of the push-button face plate are transparent or 15 translucent.

On the pressure of a landing push button, the corresponding cross-arm on the controller is rendered electrically sensitive, and the push button becomes and remains illuminated. On the approach of an elevator in the desired direction, a wiper associated with the traveling solenoid, contacts with the sensitized cross-arm and causes the cross-arm to rotate on its axis; thus moving the contact fingers corresponding with other elevators out of contacting position, and provides against interference. The related movements then cause electric impulses, corresponding (in number and in direction of current flow) with the solenoid in contact with the cross-arm, to be 30 transmitted to the related polarized magnet at the landing push button. The direction of impulse movement of the polarized magnet armature determines the set of audible and visual signals which is affected. The number of transmitted impulses determines the number of strokes on a sound producing medium, or the selection of an announcement by reproduced human speech, and also determines the number of light baffle openings which will be cleared. If the serving 34 elevator is in the bank of elevators on the side of the landing on which the actuated push button is located, and to the left of that button, a strip of light will appear, advancing in steps on the push button face plate to the left of the actuated 44 button. The length of this strip of light is determined by the number of impulses. If the serving elevator is to the right, the strip of light will extend to the right. The color of the illuminating of the push button and of the strip of 50 light is different for the two buttons.

If the serving elevator is in the bank of elevators on the side of the landing opposite to that on which the actuated button is located, a separate space on the push button face plate is 55

lumined to read "Opposite", and the audible and visual indications as above described are provided at the push button plate at the side of the landing at which the approaching elevator is located.

It will be apparent that for a total of sixteen elevators positioned as described, the maximum number of impulses required from any traveling solenoid is four. If, instead of being opposite, 10 the doorways of remote elevators are behind projecting columns or around corners, the wording of the separate indicating visual signal is changed, or the signal is of a distinctive color. If the distance between push buttons is considerable, a distinctive audible signal accompanies the visual "Remote" signal. If some of the remote elevators are opposite and some around the corner, the wording which appears at the "Remote" visual signal face corresponds with the location 20 of the serving elevator.

At the proper time, the signals in the car function and, after the landing has been served, all parts are automatically returned to normal.

No disrupting of a live electric circuit takes 25 place at any push button, and at the points in the system at which the opening of a live circuit takes place, a quick action is provided. The push buttons and their associated parts are enclosed in dust-proof and damp-proof cases and the controller parts are also protected. These provisions, together with concentration of observer and observed, and the aid of reflectors, permit of dependable use of small and light weight parts and the entire system is adapted to mass production and, if desired, to mass shipment of parts and local assembly.

The nature of the system permits of the addition of other useful functions.

The foregoing and other features of my invention will now be described in conjunction with the accompanying diagrammatic drawings.

The description of each of the figures should read:

Fig. 1 is a front view of a push button box, 45 showing an up and a down push button, visual signal spaces adjacent to each push button and slotted plates covering audible signal elements.

Fig. 2 shows the interior of the push button box.

Fig. 3 is a side view of the push button box.

50 Figs. 4 and 5 show the hinged mounting of the cover of the push button box. The former shows the box with the cover closed and the latter with the cover opened to provide free access.

Fig. 6 is an end view of the push button box 55 showing the optical arrangement whereby each push button and the visual signal spaces to the right and left are illuminated from a single source of light.

Figs. 7 and 7a are front views of the pawl and 60 ratchet movement by which the light barrier is vertically moved to permit the source of light to successively illuminate the visual signal spaces to the right and left of the push button; and is returned to normal position.

65 Figs. 8 and 8a are side views showing the mechanical relation between the push button and its corresponding electrical contact, holding magnet and the releasing mechanism for returning the light barrier to normal position.

70 Fig. 9 is a side view, showing the relative position of the sources of light for illuminating the "Remote" visual signal above the up button or below the down button.

Fig. 10 is a front view showing that the contact 75 arm moved by the push button is recessed to per-

mit the illuminating of the push button from its source of light.

Fig. 11 is a front view of the carrier with its associated guides, contacts and mechanism for moving the carrier in geared relation to the movement of its corresponding elevator car. This carrier is a part of the controller and there is one carrier corresponding with each elevator car.

Fig. 12 is a side view of Fig. 11.

Fig. 13 is a view looking down upon the controller and showing the guides corresponding with eight carriers, together with the relative positions of the cross arms corresponding with the several floors.

Fig. 14 is a front elevation of Fig. 13.

Fig. 15 is a plan view of a pivoted plate which supports the bell-crank contacting levers on the upper part of the carrier. One bell-crank contacts with the up cross-arms when its corresponding elevator is traveling up, and the other bell-crank contacts with the down cross-arms when its corresponding elevator is traveling down.

Fig. 16 is a front view of the carrier, showing the mechanism for returning a cross-arm to normal.

Fig. 17 is a side view of Fig. 16.

Fig. 18 shows the manner of engagement of the mechanism in Fig. 16 with an arm which is mounted on the stationary guide, and which arm is moved into engagement position by the rising 30 of the solenoid plunger on the carrier.

Fig. 19 is a variation of the arm mentioned in describing Fig. 18, and is employed at terminals.

Fig. 20 shows the manner in which a cross-arm pivots on the left hand side of the controller as 35 shown in Fig. 14.

Fig. 21 shows the manner in which a cross-arm pivots on the righthand side of the controller as shown in Fig. 14. It also shows how the movement of the cross-arm on its axis performs certain electrical switching functions on the right-hand pivot block. The electrical connections are shown in Fig. 54.

Figs. 22, 23, 24, 25 and 26 show details of the righthand pivot block.

Fig. 27 shows a side view of the carrier with a reversing switch mounted thereon. This reversing switch is functioned at terminals by cams 44 in Fig. 14.

Fig. 28 is a plan view of Fig. 27.

Fig. 29 is a front view of the reversing switch in Fig. 27.

Figs. 30, 31 and 32 are details of the rocker arm and stationary cam for functioning the reversing switch in Fig. 27.

Figs. 33, 34, and 35 show details having to do with proper signaling when a car is at a terminal floor.

Figs. 36, 37, 38 and 39 show the electrical relations obtaining between positive and negative 60 line under four different conditions in the functioning of the system.

Fig. 40 shows the wiring connections between the push button boxes and the several parts of the controller.

Figs. 41, 42, 43, 44, 45, 46, 47, 48 and 49 show details of the controller.

Fig. 50 shows the method of providing first an audible and then a visual signal on the approach 70 of a car to a calling floor.

Fig. 51 is a wiring diagram referring to two "Remote" locations.

Fig. 52 indicates the electrical connections between a receptionist's desk and the elevator push buttons at the corresponding floor.

Fig. 53 shows the electrical connections for providing human voice announcements at landings.

Fig. 54 shows the electrical connections of the righthand pivot block shown in Fig. 21.

Fig. 55 shows the method of providing for night service signals.

In the drawings, similar parts are indicated by similar reference characters in the several figures.

Figures 1, 2, 3, 4, 5 and 6 show several views of a push button box. Larger scale drawings of working parts are shown in other figures.

Figure 1 shows the face plate of a push button box suitable for the sixteen elevator installation mentioned. 10 is the push button, 11 is the illuminable face of the push button, 1 is an illuminable face in the face plate, of which spaces four are shown on each side of the up push button and four are shown on each side of the down push button. 2 is the illuminable space for the "Remote" signal, 3 is a removable plate covering a recess in the face plate. This plate is provided with openings to allow of the emission of sound. 4 is an opening for the insertion of a key for locking and unlocking the face plate.

Fig. 2 shows the push button box with the front surface of the face plate removed. 5 is the casing of the push button box. 6 is a section which is part of the face plate. This webbed section stiffens the face plate and supports internal parts. 7 is a light baffle, of which there are four. 8 is an electro-magnet, of which there are two; one corresponding with each button. 9 is a polarized electro-magnet: only one is shown, but there are two; one corresponding with each button. 12 is the polarized armature of the magnet, which is normally held in midway position between the magnet polepieces by springs 13, and which moves an arm 14, carrying two pawls 15; the pawls being arranged to engage in opposite directions and being mounted on opposite faces of the arm 14. 16 indicates the location of supports for locking devices for two toothed segments actuated by the pawls 15. These segments rotate on supports independently mounted, and each is positioned to be operatively engaged by its corresponding pawl 15 and locking device. An extension attached to the hub of one segment extends to the right and an extension attached to the hub of the other segment extends to the left. 17 indicates the position of the axis of rotation of these two segments and dotted lines 18 indicate the approximate angular movement of each hub extension. 19 is an insulated electric switch. Only one of these switches is shown, but two are supplied in conjunction with each button; each being actuated by one of the above described hub extensions. 24 is a shaft on which are securely mounted the polarized armature 12, the arm 14 carrying the two pawls, and hammer actuators 21. 22 is the recess in the face plate. Only one recess is shown, but there is one corresponding with each button. 23 is a hinged hammer arranged to impinge upon a sound producing element which I have shown as a clock coil 24. There are two hammers and two clock coils in each recess. The upper and lower halves of the push button box are identical, save for the arrangement above and below a horizontal. As the upper and lower light baffles move toward the horizontal middle of the box, when actuated, and I prefer to suspend them in each case, rods 25 are provided for functioning the lower baffles from their respective segments. Hence, while the two baffles 7 corresponding with the up push button move by gravity toward the horizontal middle of

the box when permitted to do so by arms as represented by lines 18, and are returned by them against gravity, those corresponding with the down push button move by spring pressure applied to their suspensions, toward the horizontal middle of the box when permitted to do so by their corresponding arms as represented by lines 18, and are returned by them against spring pressure. I permit, rather than force, the movement of light baffles 7 and their suspensions, to open light ports, in order to reduce the mass of the parts to be moved by the quick magnet actuated movement in opening the light ports. The movement of the suspensions and baffles may follow more leisurely.

Fig. 3 shows a side elevation of the face plate with parts attached. 26 is an electric globe for illuminating "Remote" space 2. 27 is a stationary tapered metal light baffle extending between movable light baffle 7 and illuminable spaces 1. Stationary light baffle 27 is divided to correspond with the several illuminable spaces 1. The purpose of tapering is to reduce the necessary movement of movable light baffle 7. Radiation of light rays when projected through the small opening of light baffle space of 27, illuminates the entire area of the corresponding illuminable space 1. When direct current is passed in one direction through polarized magnet 9, its polarized armature 12 is moved in one direction, and when passed in the opposite direction its armature is moved in the opposite direction. Corresponding movement takes place in arm 14 and hammer actuators 21. The pressure of springs 13 returns all to normal position when magnet 9 is de-energized. Each energized movement of arm 14 causes one of the pawls 15 to move its corresponding toothed segment 28 the distance of one tooth on the segment. As will be later described, this movement being transmitted through the extension attached to the hub of the segment permits corresponding normally open switch 19 to close, permits corresponding light baffle 7 to allow light rays to illuminate corresponding space 1 nearest to corresponding button and causes corresponding hinged hammer 23 to impinge sharply on corresponding clock coil 24. Corresponding lock 16 holds actuated segment 28 in actuated position and if polarized magnet 9 is de-energized and again energized in the same direction, segment 28 will be advanced another tooth, the second space 1 from the button will be illuminated and a second blow will be delivered to the clock coil. Illuminating of the third and fourth spaces 1, and the third and fourth sounding of clock coil 24 would similarly result from the third and fourth energizing of magnet 9.

The relative positions of electro-magnets 8 is indicated by end views of their respective coils. 29 is a stationary light baffle between the two sets of buttons and illuminable spaces. 30 is a threaded rod, turned by a key inserted through opening 4 and engaging in a boss on the inside of casing 5 for the purpose of drawing face plate Fig. 1 into compression contact with packing 31, or otherwise locking and unlocking face plate Fig. 1 with respect to its casing 5.

Fig. 4 is a section view of the side of casing 5, showing conduit entering from the hoistway side of the box. The flexible electrical conductors 70 entering the box are sealed at the conduit opening, packing rings are provided at each push button, the opening between recess 22 and the interior of the push button box is filled with shaft 34, which may be packed if necessary, and 75

the interior is sealed at all other points by packing 31 against dust, dampness or gas.

By means of hinged arms 32, face plate Fig. 1 with the parts mounted thereon is supported in casing 5 and may be quickly opened out as shown in Fig. 5, exposing all interior parts to view and holding them in convenient position for any purpose.

Fig. 6 is a plan view showing the divisions of stationary light baffle 27 on one side of the push button. A similar light baffle is provided on the opposite side of the push button, but this latter has been cut away to show the relative position of the hub extension of segment 28 and the manner in which it intercepts one arm of the hinged suspension for movable light baffle 7. The two arms constituting this suspension are secured to one shaft which hinges at 33. 20 is an electric globe which constitutes the source of light for illuminating one push button and its related illuminable spaces other than "Remote" signal 2. 35 indicates reflectors for directing rays from source of light 20, each to its corresponding illuminable space 1 to the left of its corresponding button, when the position of corresponding movable light baffle 7 permits such rays to pass. Similar reflectors are provided at the right. 36 are reflectors for directing rays from source of light 20 to illuminable face 11 of push button 10, and to reflectors 35. A separate source of light and a separate set of associated reflectors is related to each push button. While not always shown, I provide reflectors for concentrating or directing rays of light in conjunction with all sources of light employed throughout the system.

Figs. 7 and 7a are front elevations and Figs. 8 and 8a are side elevations of certain push button box parts. In Fig. 8a, 37 is the coil, 38 is one of the polepieces, and 39 is the armature of one of the electro-magnets 8. Fig. 8 shows the coil of magnet 8 with the polepiece removed to permit a clearer view of the other parts. Armature 39 is here shown in energized or magnetically closed position against the tension of spring 40. 45 having been brought to that position by momentary pressure of push button 10 and intermediary 41, which latter, together with the push button, were returned to normal by spring 167 immediately on the removal of manual pressure on push button 10. In closing, insulated extension 42 of armature 39 closed switch 43, which is made up of two leaves bent at 90 degrees to permit of their being attached to the magnet support. The closing of this switch completed an electric circuit which retained the electro-magnet in closed position. Also attached to armature 39 is 90 degrees arm 44 supporting pin 45 and the lower end of rod 46. 47 is another 90 degrees arm pivoting at 48, having its horizontal section supported by pin 45, and itself supporting rod 49. As shown, rods 46 and 49 are in their retracted position. When the electric circuit through coil 37 is opened, spring 40 causes arm 44 to rotate on its axis 50 and extend rod 46. Simultaneously, 65 pin 45 causes arm 47 to rotate on its axis 48 and extend rod 49. 51 is the suspension, pivoted at 33, of movable light baffle 7.

Referring to Fig. 7, pawl 15 on the front face of arm 14 normally rests in the recess of tooth of 70 52 of correspondingly broad faced segment 28, which is normally spring-held against a stop. Its hub extension at right angles to the path of suspension 51 prevents the latter from lowering light baffle 7. Rod 46 being in retracted position, 75 pawl 54 on lock 16 is ready to engage in part of

broad tooth 52, if pawl 15 already engaging in broad tooth 52 advances it to engagement position. A momentary electric impulse in polarized magnet 9 causes segment 28 to be advanced one tooth, when it is immediately locked by pawl 54. 5 The outer end of hub extension 53 moves downward a sufficient distance to permit switch 19 in Fig. 2 to close, and to permit suspension 51 to lower movable light baffle 7 a sufficient distance to clear the light port of corresponding space 1. 10 Successive impulses clear successive light ports to the left of the push button. A similar arrangement to the right, and electric impulses in the opposite direction through the polarized electro-magnet will open a switch 19 and clear 15 light ports to the right of the push button. Without further provision, the movement of arm 14 to the right, to function the segment to the right, would also carry the pawl 15 on the front face one tooth to the right and interference with its 20 corresponding segment would result during the return stroke of arm 14 to midway position. Referring to Fig. 7a, an extension 55 on pawl 15 mechanically contacts with lug 56 attached to locking device arm 16 and raises front pawl 15 25 out of engagement position on the right hand stroke. A similar provision prevents interference on return from the left hand stroke. When magnet 8 is deenergized, rod 46 is extended and, with it, lug 56 which impinges at an angle with pawl 30 extension 55, and also raises arm 16 pivoted at 51, carrying pawl 54, and whichever segment has been moved out of normal position is returned to normal by its spring, and simultaneously any open light ports are closed, switch 19 is opened 35 and switch 43, which has opened with the return of armature 39 to normal, has darkened source of light 20 which is in series with coil 37.

Fig. 9 shows two electric bulbs 26 in recess 22, instead of one. These are separated by a light 40 barrier and permit of two separate "Remote" signals in space 2. This permits of indicating that the serving elevator is opposite or that it is around a corner.

Fig. 10 indicates that intermediary 41 is forked, 45 to avoid interference with the passage of rays from source of light 20 to push button illuminable face 11.

I will now point out the construction of the controller to which the previously described push 50 button box is electrically connected. Here also I show assembly drawings, and larger scale drawings of parts.

In Fig. 11 I show a front elevation of a traveling carrier 58 with four insulated guide shoes 59, running on left hand guide 60 and right hand guide 61. This carrier supports solenoid 62, whose plunger 63 and its extension 64 are guided by frictionless rollers 65. On the bottom of plunger 63 is cup 66 sliding in air chamber 67 at 60 the bottom of which is located adjustable valve 68. The plunger rises freely but is checked in its descent by compression of air in chamber 67. 69 is a cable which leads to a counterweight which balances carrier 58, but is insulated from both 65 carrier and counterweight. 70 is an up cross-arm and 71 a down cross-arm, each carrying a contact finger 72 corresponding with each carrier, and each cross-arm pivoting in pivot block 73 and contact pivot block 74, adjustably mounted on pivot block rails 75. Figure 12 is a side elevation of carrier 58 and related parts. As carrier 58 is moved up and down in its guides, up and down bell cranks 76 and 77 contact with the respective up and down cross-arm fingers 75

72, through respective light spring contacts 78 attached to the same base as the bell cranks, which base is swivel plate 79. Contact 78 as shown is for the down bell crank. For the up bell crank, the vertical position of a corresponding contact 78 is reversed: that is, the free end of this contact 78 is below, instead of above. On the up trip, bell crank 76 alone contacts with cross-arms, and this contacting takes place with 0 up cross-arms 70 only. On the down trip, the contacting is confined to bell crank 77 and down cross-arms 71. When the contacting element of the carrier contacts with a cross-arm which has been sensitized by the pressure of a push 5 button connected to that cross-arm, an electric circuit is completed through solenoid 62, whose plunger jumps up and, through the medium of insulated U-arm 80 mounted on plunger extension 64, impinges with whichever bell crank is 0 in alignment with U-arm 80, and rotates the contacted cross-arm on its axis 81. This moves all other contacting fingers on that cross-arm out of contacting position for all other carriers and the cross-arm is locked in this rotated position 5 at contact pivot block 74. Immediately the bell crank is actuated, it is locked in extended position by spring actuated catch 82, which also raises tripper bar 93, and a pair of normally closed contacts 93a are simultaneously opened. Electrical contact is thus maintained between the cross-arm and swivel plate 79, through the medium of light spring wiper contact 78, whose free end is prevented from extending too far, by stop 82, which is also attached to the swivel plate 79. Left guide cam 83 is adjustably secured to left hand guide 68, and has a hinged portion 84. In rising, the top of plunger extension 64 impinged upon cam setter 85, normally spring-held in position shown, which in turn impinged upon hinged portion 84, moving it to the position indicated by the dotted line and bringing it into contact alignment with contacts 86 and 87 mounted on the carrier, where hinged portion 84 was locked. The rotation of the cross-arm caused a switch on contact pivot block 74 to interrupt the circuit through solenoid 62, whose plunger immediately started to descend, leaving the actuated bell crank 76 or 77, and the cam hinged portion 84 in locked position. Impulse generator contactor 88 is mounted on but insulated from plunger extension 64, which also carries insulation block 89. Insulated impulse generator arm 90 is pivoted on the carrier with a friction washer bearing against its hub. During the rise of the plunger, no electrical contact existed between 90 and 88. During the descent of the plunger, arm 90 contacts with contactor 88 and, as the latter successively contacts with stationary contacts 91 mounted on the carrier, electric impulses are transmitted to a conductor connected to as many of these contacts as there may be on that carrier; which may be one, two, three or four, depending upon the position of its corresponding elevator to the left or to the right of the push button box.

When the pivot block switch opened the circuit through solenoid 62, it transferred the cross-arm connection to a separate conductor leading to the corresponding polarized magnet in its corresponding push button box. The generated impulses are transmitted through wiping contact 78 to the cross-arm and thence to the polarized magnet in the push button box. As plunger extension 64 approaches the bottom of its stroke, insulated strap 92 extending from the top of 64

moves hinged tripper bar 93 against catch 82 and unlocks the actuated bell crank, which is spring returned to normal, and with it, wiping spring 78. The downward movement of tripper bar 93 also returns contacts 93a to their closed position. 94 is an insulated reversing switch mounted on the carrier. 95 is a sprocket wheel meshing with a driving chain actuated by the corresponding elevator mechanism. Secured to its shaft is a beveled gear which meshes with another beveled gear secured to screw 96, which extends back of the carrier for the full height of the latter's travel. 97 is a friction nut, threaded on screw 96. This friction nut, which is a well known device in elevator signal practice, bears at top and bottom against shoulders 98 extending from the back of the carrier frame, and has a projection 99 which extends through an opening in the carrier frame and engages with insulated projections mounted on swivel plate 79. When screw 96 is caused to rotate by the movement of its corresponding elevator mechanism, friction nut 97 rotates with it until a positive stop is encountered, when the continued rotation of screw 96 causes nut 97 to travel up or down and moves with it carrier 58. While rotating with the screw it rotated swivel plate 79 on its insulated axis 100, mounted on the carrier. In moving through part of a revolution, swivel plate 79 brought either bell crank 76 or bell crank 77 into contacting position with its respective cross-arm fingers 72 and into impinging position with its respective leg of U-arm 80, and through projection 101 mounted on the swivel plate, moved the pivoted arm of reversing switch 94 into contacting position with one or the other of its two sets of stationary contacts. No provision has yet been shown for returning locked hinged portion 84 to normal, but this will be later described, as will also the purpose of stationary contact 102 mounted on the carrier.

The combination of provisions for a multiplicity of elevators results in a controller whose guide and cross-arm arrangement, in combination with the arrangement of other parts, is shown in plan view Fig. 13 and front elevation Fig. 14.

Fig. 13 shows the controller with the top removed and the arrangement corresponding with two banks of four elevators each. For two banks of eight elevators each, the width of the controller would be increased and, with it, the reach of the cross-arms, but the other previously described equipment would remain the same.

Fig. 14 shows one face of the controller, of which both faces are substantially the same, except that hinges and contact pivot blocks are at the same side of the controller, for convenience in effecting electrical connections. 103 is a shaft, instead of a sprocket chain, geared to the elevator mechanism, and has secured to its controller end a bevel gear which meshes with the bevel gear secured to screw 96, and thus furnishes related movement to the carrier. 104 indicates the position of the counterweight cable. The supports for the cross-arms are mounted on a web stiffened frame 105 hinged at 106, which is on the contacting line between the carriers and the cross-arms. When closed, this frame seals against the controller side walls and its top and bottom. Hinged at 107 on frame 105 are doors 108 with glass fronts which, when closed, seal against frame 105. Hinges 106 have tubular centers through which the electrical conductors pass to compartment 109, into which the hoistway electrical conductors are also led through con-

duit sealed at the point of entrance, and in this compartment certain auxiliary magnets are mounted. This compartment is provided with a glass front door, which, when closed, seals against the controller walls, and all of the doors and the hinged frames may be locked. There is thus provided a protected controller, all parts of which are open to observation. To permit of swinging the hinged frame 105 without effort and without damage to the conductors leading to the cross-arm contact pivot blocks, these conductors are twisted into a cable and some distance intervenes between the point of attachment of this cable to the frame and the tubular hinge. Counterweight sheave 109 is insulated from the controller and there is an insulator in the cable between this sheave and the counterweight support. Counterweight sheave 109 and guides 60 and 61 therefore form three electrical connecting points, other than the cross-arms, between each carrier and the stationary part of the controller.

Fig. 15 shows a plan view of swivel plate 79 and related parts of the controller. It also shows the means of returning a cross-arm to normal, after the functions pertaining to its initial movement have been performed.

Fig. 16, which shows the front elevation of the parts of this returning device attached to the carrier and Fig. 17, which shows a side elevation of these parts, must be considered in this connection. Mounted on each carrier are two side bars 110; one slotted at both ends and the other slotted at one end. In these slots are adjustable supports for the bearings of shafts 111 and 112. Secured to shaft 111 are arms 113 and 114, and secured to shaft 112 are arms 115 and 116. I have previously described the manner in which the jumping up of solenoid plunger 63, on the carrier, moved hinged portion 84 on left hand guide cam 83 and left it locked. On the up trip, the continued travel of the carrier brings arm 113 into mechanical contact with hinged portion 84 and causes arm 114 to rotate on axis 111. Mounted on up cross-arm 70, in addition to contact finger 72 is return finger 117, corresponding with each carrier. Arm 114 does not contact with return finger 117 either when cross-arm 70 is in normal position or when it is in rotated position, except when arm 114 is rotated on its axis 111, when it returns the cross-arm to normal. Fig. 18 shows the manner of the engagement of its related arm 113 with hinged portion 84 of stationary cam 83. Catch 118 on arm 113 engages with insert leaf 119 on hinged portion 84, when the latter is in locked position. The continued movement of the carrier, not only causes related arm 114 to rotate on axis 111 and thus return cross-arm 70 to normal, but in rotating on axis 111, the arc described by the catch extremity of arm 113 causes it to bear upon spring lock 120 on cam 83 and release hinged portion 84, which is spring-returned to normal. After passing cam 83, connected arms 113 and 114 are spring-returned to normal. The contacting extremities of both arms are insulated. Catch 118 on arm 113 does not engage on the down trip. The action of arms 115 and 116 is similar for the return of down cross-arm 71 and hinged portion 84 on the down trip. When in locked position, tip 121 on hinged portion 84, which is in electrical connection with left hand guide 60, electrically contacts with contacts 86 and 87 on the carrier, when the traveling position of the carrier causes this to occur.

Fig. 20 shows one end of a cross-arm and Fig. 21 the other end. The cross-arm construction

shown is triangular tubing with the contacting and return fingers spot-welded thereon. This is made up in long strips, cut to length to suit the controller to be assembled, fitted with cross-arm ends, adjusted in a jig and is ready for the controller. Cross-arm end 121 fits inside of this tubing and is secured, and forms a pivot bearing. Cross-arm end 122 is similarly mounted, and includes a pivot bearing cam 123, pin 124 and pin 125. A side elevation of this end is shown in Fig. 23. 126 is a movable pivot.

Figs. 21, 22 and 24 show three views of contact pivot block 14. Both 13 and 14 are shown as double pivot blocks to serve two cross-arms, but either may be halved to serve one cross-arm. These pivot blocks are of moulded insulating material, with open slots to permit of their being slipped onto the side of their respective supports 15, where they are secured by setscrews 127. Supports 15 are suitably scored to facilitate quick and accurate locating of the pivot blocks and thus the cross-arms with respect to the travel of the carriers. As supports 15 are of rolled stock, pivot blocks are moulded, cross-arms are tubing and all parts are jigged, the relations are accurate and permit of the use of racks for the quick removal and replacement of one or a multiplicity of cross-arms without disturbing others. Should it be desired to accomplish such change without shutting down the elevators, one rack is used for removal and another rack, loaded with duplicate cross-arms, is used for replacement. For a single cross-arm, the rack is already adjusted with its locating fingers arranged to bear against the upper faces of the respective pivot blocks, and against supports 15, and it is thus supported. The cross-arm is then manually rotated out of contacting position for the carriers, spring grips on the rack then grasp the cross-arm without disturbing its alignment with its pivots, the pivots 126 are manually withdrawn and the rack, with the cross-arm, is removed. The other rack, holding a similarly secured duplicate cross-arm, is placed in position, the pivots 126 are pushed into place, the spring grips grasping the cross-arm are released and the cross-arm is manually rotated to contacting position with the carrier. The new cross-arm is now in service, and the rack may be removed. The functioning of the system has not been interfered with save in respect to such contacting functions as might possibly have been called for by that cross-arm position during the brief period in which no cross-arm was in contacting position to respond. For the handling of several cross-arms at one time, if the vertical distances between pivot blocks vary to correspond with unequal distances between floors, the vertical distances between the spring grips on the rack frame are first adjusted on both racks, after which each cross-arm is handled as above described.

In addition to pivoting, the functions of contact pivot block 14 in conjunction with its corresponding cross-arm, are to provide an electrical connection between the cross-arm and the corresponding push button circuit when the cross-arm is in normal position, and when the cross-arm is rotated, to transfer this connection to the corresponding polarized magnet, to open a non-interference circuit between the two faces of the controller when such controller arrangement is employed for two banks of elevators connected to the same system, and to lock the cross-arm in rotated position. These functions also include the momentary interrupting of the

continuity of the corresponding push button circuit across the current supply line at the time of the return of the cross-arm to normal, in order to provide for the simultaneous return of actuated push button box parts to normal. In performing these functions, the opening of all live circuits at the push button contacts is eliminated. A wiring diagram of the connections between the parts of this pivot block is shown in Fig. 54. Contact pivot block 14 mounts the parts corresponding with one up and one down cross-arm, which are identical save for a right and a left arrangement. On support 128 are pivoted two flyers 129 and 130, the latter being insulated from the support. Normally, these two flyers are held in the same angular pivoted position on their common support by contact springs 131 and 132, which are always in spring contact and electrical contact with their respective flyers. When the cross arm is rotated, pin 124 actuates flyer 129 on the axis of its support 128, and through insulated plate 133, which is a part of flyer 129, rotates its flyer 130 and thereby maintains continuity of electrical connection between spring contacts 131 and 132. Flyer 130 is also brought into connection with contact 144 which is permanently connected to spring contact 131. On the opposite side of the axis of flyer 130 is insulated projection 134 which is engaged by spring pressed catch 135, pivoted on stud 136, which is mounted on support 128. Simultaneously, insulated finger 137 on flyer 129 has moved contact 138 out of electrical connection with contact 139 and into connection with contact 140, thus opening the established circuit through solenoid 62 on carrier 58 and transferring the connection of the cross-arm from the push button circuit to the polarized magnet circuit. As the rotating of the cross-arm resulted from the jump-up of the solenoid plunger on the carrier, the above movements were quick. Simultaneously, cam 123, of which one end had normally engaged with latch 141 secured to the bottom of support 128 was rotated to the position where its other end engaged with latch 141 and the cross-arm was thus locked in rotated position. Figs. 25 and 26 show other views of this latch. Simultaneously, pin 125 moved contact 142 out of connection with contact 143, thus disconnecting the corresponding cross-arm on the opposite face of the controller and rendering it dead, to provide against interference. As carrier solenoid 62 has been de-energized, its plunger descends, transmitting electric impulses through the contacted cross-arm to the connected polarized magnet in the push button box. As the cross-arm is returned to normal, pin 124 returns flyer 129 and with it contacts 138 and 142 to normal, but flyer 130 is prevented from returning by latch 135. This results in the opening of an air gap between plate 133 on flyer 129 and flyer 130, but as contact 144 is touching flyer 130 and is likewise permanently connected to contact spring 131, the continuity of electrical connection between the two contact springs 131 and 132 is maintained. On nearing the completion of its return to normal, flyer 129 presses against the lower extremity of catch 135, which releases flyer 130, whose spring 132 returns it to normal contacting position with plate 133 on flyer 129, but 130 leaves contact 144 before it reaches its normal contacting position and the continuity of the push button circuit between its line terminals is thus momentarily interrupted, and the push button holding magnet releases.

Fig. 27 shows a front elevation and Fig. 28 a plan view of insulated reversing switch 145 on carrier 58, which is actuated by the traveling movement of the carrier as it approaches cams 146 adjustably secured to guide 61 at the terminals of the carrier's travel, as shown in Fig. 14. Fig. 29 shows a side elevation of the reversing switch movable arm and of the stationary contacts, and Fig. 30 a side elevation of the shaft rocking lever which engages with cam 146 at each end of the carrier's travel. Figs. 31 and 32 show other views of cam 146.

By reference to Fig. 28 and to Figs. 13 and 14, it will be observed that any carrier may be removed from the controller by swinging hinged frame 105, detaching the counter-weight cable 68 and removing two shoes 59, when the carrier may be lifted out as a unit. Should it be desired to remove a carrier without interfering with the operative functioning of other carriers, the carrier is run below the lowest cross-arm, or to a space between cross-arms if express elevator service makes intermediate space available, and there removed without swinging frame 105. As the described carrier units are identical, any unit may be quickly replaced by another unit.

To allow time for an intending passenger to place himself at the doorway of the serving elevator before the elevator arrives at that doorway, it has been customary to arrange flashlight systems to signal the landing when the serving elevator is a little less than three floors away, but, to avoid confusing the operator, it has been necessary to withhold the stopping signal to the operator in the car until the car has passed the floor immediately preceding that at which the stop is to be made. When a car, which is subject to call from all floors, is at a terminal floor, it is obvious that special provision should be made for calls which are only one or two floors away. Figs. 33, 34, 35, 42, 43, 44, and 19 have to do with such provision. Referring to Fig. 11, it will be observed that with the carrier traveling on the up trip, the vertical position of the carrier with respect to cam 83 represents the contacting position for the latter's associated cross-arms, and the functioning of the signals at the corresponding landing. The vertical distance between stationary cam 83 and the nearer end of lower contact 86 mounted on the carrier represents the distance to be traveled by the carrier before the signal in the car functions, and the further distance represented by the length of contact 86 approximately represents the additional distance to be traveled before all corresponding parts are returned to normal; the actual distance being determined by the parts shown in Figs. 16 and 17. Referring now to Fig. 14, let us assume that the controller applies to a sixty floor installation. Then, up cross-arm which I will individually designate as 147, represents the contacting cross-arm for the sixtieth floor, but the carrier will continue to travel up for a distance corresponding with approximately three more floors before it reaches its terminal. If a button has been pressed at the sixtieth floor, the serving elevator rotates cross-arm 147 and sets the corresponding left guide cam 83. The corresponding signals function at the push button box at the sixtieth floor. As this is a terminal floor with no up button, but only a down button, these signals function as down signals. For intermediate floors, the parts are returned to normal as the car passes the floor, but it does not pass the terminal floor. After serving the terminal, it reverses and starts

on its down trip. Hence, cross-arm 147 must be returned by a special provision. Figs. 33, 34 and 35 show three views of such provision. Straddle cam 148 is adjustably secured to left hand guide 60, straddling the cam 83. The lower toe of its movable member 149 is spring-held against hinged portion 84 of cam 83. The normal positions of both are shown by dotted lines in Fig. 35. If a button has been pressed at the sixtieth floor, the rotating of cross-arm 147 has brought both 84 and 149 into the full line or engaging positions. A third arm 150 has been secured to shaft 111 shown in Figs. 16 and 17. In these figures, arm 114 is shown on the carrier side of side bar 110. This third arm 150 occupies approximately the same position on the other side of side bar 110. For intermediate floors, arm 113 engages with hinged portion 84 of cam 83 on the up trip and rotates shaft 111, but does not engage on the down trip. Arm 150 does not engage with hinged arm 149 of straddle cam 148 when the carrier is moving up, but it does engage when the carrier starts down from its terminal, and thus rotates shaft 111, returning cross-arm 147 and related cam 83 to normal in manner similar to the action of arm 113 with respect to similar intermediate parts. When the carrier is at its upper terminal, it is in contacting position for down cross-arm 151. Through connections which will be later described, if a down push button on any or all of floors fifty-nine, fifty-eight or fifty-seven have been pressed, as soon as the serving elevator starts down, its carrier will effectively contact with cross-arm 151, rotating this cross-arm and setting corresponding cam 83. The return of these at the proper time will be effected by arm 115 in Figs. 16 and 17, as has been previously described. Cross-arm 152 is the down cross-arm for the fifty-sixth floor and 153 is the down cross-arm for the fifty-fifth floor. Their functioning is the same as that of any other intermediate cross-arm. I will now describe the interrelations between the down signal parts pertaining to the fifty-ninth, fifty-eighth and fifty-seventh floors.

In Fig. 14, 154 is the down cross-arm pertaining to the fifty-ninth floor, and 155 is the down cross-arm pertaining to the fifty-eighth floor. Neither has any contact finger 72 but both have down return fingers 117. I will refer to them as front cross-arms. In Fig. 13 are indicated the plan locations of magnets 156 and back cross-arms 157 as shown in Fig. 42. Through the medium of the intervening pin and fork, the movement of the armature of magnet 156 simultaneously rotates both back cross-arms 157, and a cam friction on one of the back cross-arms, similar to the cam friction for holding a cross-arm in rotated position as shown in Figs. 21 and 23, locks the cross-arms in rotated position. Through the medium of arm 222, which is secured to back cross-arm 157, pusher 223, which is also supported by hinged arm 224, is projected through the opening in frame 105 on the face of the controller, until 223 impinges upon the left end of cross-arm 154 and rotates it. Front cross-arm 154 is equipped with a spring which tends to keep it in normal position. When it is rotated, it is maintained in rotated position only so long as the cam friction on back cross-arm 157 maintains it there. As the relation between pusher 223 and the front cross-arm is an impinging relation only, the swinging of controller frame 105, when desired, is not interfered with. A separate but similar arrangement provides for the rotating of back and front cross-arms as

represented by cross-arm position 155. A third electro-magnet 156 rotates back cross-arms corresponding with the fifty-seventh floor position, but these do not mechanically rotate the front cross-arms 151. Should the controller have only one face, the pin and fork and the parts rotated by their use would not be required. Fig. 19 shows, in effect, hinged portion of cam 83 separated into two parts; the part which I have numbered 158 being the part which is impinged upon by cam setter 85 on carrier 58 as shown in Fig. 11, which also includes the retainer for lock spring 120 of cam 83, and engagement insert leaf 119. The part which I have numbered 159 corresponds with the electrical contacting tip 121 on hinged portion 84 of cam 83. Fig. 43 shows a front elevation of the left guide cams 83 corresponding with cross-arms 154, 155 and 151, pertaining to the down signaling for floors fifty-nine, fifty-eight and fifty-seven, respectively. Cams 83 corresponding with cross-arms 154 and 155 are of the regular type as shown in Fig. 18. The hinged portion of cam 83 corresponding with cross-arm 151 is divided as shown in Fig. 19, into parts 158 and 159. 160 is a shaft on the axis of which the hinged portion of all three of these cams rotates, as does also an arm carrying part 159. Part 158 is secured to shaft 160 and when it is struck by the cam setter on the carrier, when the latter is actuated by its energized solenoid, it rotates shaft 160 and is locked by spring lock 120 on its cam 83, and when it returns to normal, it returns shaft 160 to normal. Shaft 160 is not secured to parts 84 and 159. Clutch sleeves 161 rotate with shaft 160 but may be moved laterally on shaft 160 by clutch forks mounted on their respective back cross-arms as shown in side elevation Fig. 44 when the latter are rotated by the movement of the armatures of their respective magnets 156. Each clutch sleeve has a shoulder which engages with a shoulder on respective part 84 or 159 when the corresponding clutch sleeve is moved into engagement position. If, then, the push button at the fifty-ninth, the fifty-eighth or the fifty-seventh floor is pressed prior to the rotating of shaft 160, the corresponding part 84 or 159 rotates with it, is locked with it and is spring-returned to normal when shaft 160 returns to normal. If any of the three push buttons is pressed after shaft 160 rotates, the shoulders do not engage. None of this special arrangement is necessary for terminals with relation to which the distance between the terminal floor and its next adjacent elevator service floor is equal to or in excess of the normal intermediate initial signaling distance; such as the lower terminal of an express elevator.

Fig. 41 shows a circuit breaker, the core of whose magnet is surrounded by two separate coils 162 and 163 arranged to create the same polarity. The attraction of the armature against its pole-pieces separates contacts 164 and 165. 166 is an inertia member attached to the armature. It consists of a spring mounted weight, whose spring is supported on the lower side for some distance from its attachment to the armature, but is not supported on the upper side. This inertia member slightly delays the return of the armature and prevents any possibility of chattering.

Fig. 40 is a schematic wiring diagram showing the electrical relations between the push button boxes and the controller. It represents a controller with two faces, corresponding with two banks of elevators connected to the same signal system, together with their respective cross-arms

and push button boxes. The vertical conductors in the middle of the diagram are supposedly enclosed in a single conduit running the entire height of the building to compartment 188 of the controller, where they are connected to the cross-arm pivot blocks, and guides, counterweight cables and other parts pertaining to one bank of elevators on the left and similarly to those pertaining to the other bank of elevators on the right. The connections to one push button box, consisting of an up and a down push button, each with its electro-magnet, electric globe, polarized magnet, "Remote" switches and "Remote" electric globe pertaining to one bank of elevators are shown on the left, and the connections to a similar push button box pertaining to the other bank of elevators are shown on the right. Each intermediate floor has a similar arrangement of push button boxes. For terminals, one push button and its related parts for each bank suffices. The push button boxes for the two banks of elevators are cross-connected at each floor. If the individual system includes only one bank of elevators, the "Remote" features, the cross-connected mechanical and electrical parts and the cross-connections at the floors are eliminated. In diagram 40, two sets of carrier parts are shown as related to each respective push button box as representing elevators located to the left and to the right of that push button box, and in the sixteen elevator installation previously mentioned there would be four elevators to the left and four to the right in each bank. For the left bank, the left carrier set shown would be that for the fourth elevator to the left of the push button boxes at the several landings, and the right set shown in the left bank would be that for the third elevator to the right of the push button boxes for the left bank. This is indicated by their positions with reference to circuit breaker coils 162 and 163 and to the number of impulse generator contacts 91. It will be observed that the right hand guide 61 of the left set is electrically connected to one of the energizing coils 162 on circuit breaker Fig. 41 to positive line and that the right hand guide of the right set is connected through the other energizing coil 163 of circuit breaker Fig. 41 to negative line. If there were eight elevators in this bank, there would be four circuit breakers for the bank, and each would have a coil connected to one of the carrier sets to the left and one to the right in that bank. Referring to the carrier sets shown to the right of the diagram, representing the right bank of elevators, the left set of carrier parts would pertain to the first elevator to the left of the push button boxes at the floors for the right bank, and the carrier set to the right would pertain to the second elevator to the right of the push button boxes at the floors for the right bank of elevators. This is indicated by their positions and by the number of impulse generator contacts 91 shown in connection with each. If there were eight elevators in the right bank, they would be connected in pairs with respect to circuit breakers Fig. 41 as has been previously described. 70 and 71 represent the up and the down cross-arms respectively for any intermediate floor. Cross-arm 154 represents the special terminal cross-arm and 155 and 156 the related near terminal cross-arms when required as have been previously described. 168 is an electro-magnet which, when energized, opens six circuits and closes two.

Assume, now, that with the elevators operat-

ing on schedule, up push button 10 for the left bank at any intermediate landing is pressed by an intending passenger. A circuit is established from positive line, through corresponding source of light 20, electro-magnet 8, contact 169, contact 170, cross-arm momentary opening switch 171, cross-connected cross-arm momentary opening switch 172, individual resistance 173 to negative line. Current flows through this circuit, source of light 20 is energized and electro-magnet 8, which now acts as a holding magnet, maintains normally separated contacts 168 and 170 in connected position. Normally separated contact 174 has been simultaneously connected with contacts 170 and 169. The manual connecting of contact 169 with contact 170 has also resulted in establishing a circuit which affects similar parts of the push button box for the right bank of elevators. For these, circuit is established from positive line through respective source of light 20, electro-magnet 8, contact 169 of the up push button for the left bank, and its related contact 170, through the cross-arm momentary opening switches 171 and 172 and resistance 173 to negative line. It will be understood that cross-arm momentary opening switch 171 or 172 represents the combination of 132, 130, 133, 131 and 144 shown in Figs. 22 and 54. This energizes the electro-magnet of the up push button for that floor of the right bank of elevators, and the magnetically influenced movements of its armature connects together its contacts 169, 170 and 174, and I have a circuit as represented by Fig. 36. If 175 in Fig. 36 represents a point midway in the resistance values of this circuit, it also represents a point midway in the potential or voltage values of this circuit. Hence, if, while the above circuit persists, I establish a second circuit having resistance, between 175 and either side of the line, current will flow in this second circuit, but in opposite directions, depending upon the side of the line to which I connect it. It is the application of this principle that I employ to function solenoid 62 on carrier 58 and polarized magnet 8 in the push button boxes.

With the circuit established as in Fig. 36, the up push button at that floor for both banks of elevators will be illuminated and will remain illuminated, irrespective of which button has been manually actuated. The intending passenger who has pressed a button will thus be notified that his call has been registered and, so long as the button continues to be illuminated, he will know that his call continues to be registered and that he will be served by the first elevator approaching that floor on the up trip. There will be no doubt about it. If anything interferes with the registration of the call, the button will be immediately darkened, thus notifying the intending passenger, and he will again press the button to re-register his call. Any other intending passenger approaching either bank of elevators will be similarly notified.

Contacts 168, 170 and 174 are those which are grouped under the number 43 in Figs. 7 and 8a. Momentary opening switch 171 or 172 represents the arrangement of flyers 129 and 130 in conjunction with contacts 131, 132 and 144 in Fig. 22 to effect a momentary opening of the push button holding magnet circuit, and whose wiring diagram is shown in Fig. 54. It will be noted that in Fig. 40 a tap is led from the established circuit at a point which is indicated by position 175 in Fig. 36, to non-interference contacts 143, which, through their connecting contacts 142,

electrically connect through contacts 139 with up cross-arms 70 for the two banks of elevators; thus sensitizing both of these cross-arms. As has been previously pointed out, no carriers passing these cross-arms on the down trip would normally contact with these cross-arms. When, however, the carrier corresponding with the first elevator to approach the calling floor on the up trip effectively contacts with either of the two sensitized cross-arms 70, that cross-arm is rotated. The contacting may correspond with any one of the sixteen elevators in the previously mentioned installation. If it is a cross arm pertaining to the left bank of elevators, its rotating has moved it out of contacting position for any other carriers pertaining to that bank of elevators, and the pressure of pin 125 against contact 142 as shown in Fig. 21 has interrupted the latter's connection with contact 143, and cross-arm 70 pertaining to the right bank of elevators is no longer sensitized and contacting by passing carriers on the up trip will have no effect. The energizing of solenoid 62 of the effectively contacting carrier was effected by current passing through the cross-arm and the contacting bell crank to swivel plate 79 on the carrier, which is permanently connected to its contacts 93a in the solenoid circuit, and through the solenoid and reversing switches 94 and 145 to one of the insulated shoes 59 on the carrier, to left hand guide 60, which is connected to negative line. The resulting relation to the established push button circuit is shown in Fig. 37.

In rotating, left cross-arm 70 has interrupted its connection with contact 139 and connected itself through contact 140 with corresponding polarized magnet 9, one side of whose coils is already connected through contacts 174 and 170 and momentary opening switches 171 and 172 to a point in the established push button circuit represented by 175 in Fig. 36. On the descent of solenoid plunger 63 of this effectively contacting carrier, electric impulses are transmitted to corresponding polarized magnet 9. If this carrier corresponds with an elevator in that bank to the right of the push button box, the relation of the energizing circuit to the established push button circuit is shown in Fig. 38. If this carrier corresponds with an elevator in that bank to the left of the push button box, the relation of the energizing circuit to the established push button circuit is shown in Fig. 39. The number of impulses transmitted will correspond with the number of impulse generator contacts 81 on that carrier.

Simultaneously with the first movement of the armature of polarized magnet 9, one of the related "Remote" switches 19 has been closed, completing a circuit from positive line, through switch 19 and electric bulb of the "Remote" space 2 related to the up push button for the opposite bank of elevators, to negative line. The action of the polarized magnet has resulted in the illumining of one or more spaces 1 to the left or to the right of the up push button pertaining to the left bank of elevators, and in the sounding of identifying signals as has been previously described. While the up push button corresponding with the right bank of elevators still glows, no further change has taken place with respect to that push button, except the illumining of its related "Remote" space 2 which visually notifies any intending passenger who is observing that push button, that the serving elevator is on the side of the landing served by the other bank of

elevators, and he may visually establish its identity by looking at the push button box on the other side of the hall. The attention of any intending passenger facing either bank of elevators has been audibly attracted by the sound signals emanating from the left bank push button box, and these have audibly identified the serving elevator as has been previously described. Had the serving elevator been in the right bank, the "Remote" signal would have appeared in the left bank push button box and the identifying action would have taken place in the right bank push button box, through corresponding parts and circuits similarly disposed.

On comparing Fig. 37 with Fig. 36, it will be apparent that while the latter obtains, more current will flow through magnets 8 and sources of light 20. This obtains, however, only for the time required for solenoid plunger 63 to jump up. Comparing Fig. 38 with Fig. 36, an increase also occurs, but only during the brief period in which generator arm 88 is in contact on its down stroke with one of the contacts 91. In neither case does any harm occur to sources of light 20, nor to magnet 8. Comparing Fig. 39 with Fig. 36, the current increases through resistance 173 and decreases through magnets 8 and sources of light 20. When this occurs, however, the air gaps of magnets 8 are closed and they still have ample holding power, and no harm occurs to sources of light 20 nor to resistance 173. With a single bank of elevators, instead of a double bank, in the system, there would be but one magnet 8 and one source of light 20 in series with resistance 173, and resistance values would be adjusted to correspond.

The connections for the down push buttons are relatively the same as those for the up buttons, but as the down cross-arms rotate in the opposite direction, the corresponding contacts are oppositely disposed as compared with those related to the up cross-arms.

The purpose of circuit breaker Fig. 41 whose coils 162 and 163 are shown in Fig. 40, is to avoid any possibility of short circuit due to two carriers, whose right hand guides are connected to opposite sides of the line, effectively contacting with the same cross-arm at the same time. The instantaneous jump-up of any carrier solenoid moves the cross-arm out of contacting position for all other carriers, and further, the short circuiting could occur only with the impulse generator arms of the two carriers contacting simultaneously on the down stroke. Normal current in coil 162 or 163 does not open the circuit breaker, but excess current does.

While the floor signals have functioned for the benefit of an intending passenger, the operator of the serving elevator has, as yet, no knowledge that that floor has called, but when cross arm 70 was rotated, corresponding cam 83 had its hinged portion 84 moved into alignment and locked. I will now return to reversing switches 94 and 145 on the carrier. The former is operated by friction nut 97 and reverses whenever screw 98 reverses, irrespective of the position of carrier 88. Reversing switch 145 reverses only when mechanically contacting with cam 146 at the carrier's terminals of travel. Fig. 40 shows the reversing switches in four different relations: one with both moved to the left, thus representing their normal position for the up schedule trip; one with 145 to the left and 94 to the right; one with both to the right, representing their normal position for the down schedule trip; and one with

145 to the right and 94 to the left. When the continued up movement brings carrier contact 86 into electrical contact with aligned cam 83, a circuit is established from negative line, guide 60, cam 83, contact 86, reversing switch 94, counterweight cable 69 and counterweight sheave 109 to visual signal 176 and audible signal 177 in the corresponding elevator car, and thence to positive line. Usually, visual signal 176 is an electric globe and audible signal 177 a single stroke gong. They may be connected in series or in shunt, or only one may be employed. Reversing switch 94 renders contact 87 dead on the up trip. On the down trip 94 connects contact 87 to the car signals and renders contact 86 dead. 94 also controls the circuit through reversing switch 145. Referring to the connections of these two reversing switches as shown in Fig. 40, for the up trip, should the operator run by an intermediate landing and then reverse and run back to serve that landing, swivel plate 79 would be rotated and bell crank 77 brought into contacting position for any sensitized down cross-arm which it might encounter on the run-back. While it would mechanically contact, it would not effectively contact, for the rotating of swivel plate 79 would have also moved reversing switch 94, and under these conditions, bell crank 77 would be dead. Hence, no wrong signals would be transmitted either to the landing or to the car. The combination of these two reversing switches affords like protection on the schedule down trip.

Switch 178 is in the elevator car. Should the operator of a fully loaded car wish to run by landings without responding to possible calls, he would open this switch.

The manner of the return of controller and push button parts to normal has been described. When momentary opening switches 171 or 172 in Fig. 40 open their corresponding established push button circuit, they open it at point 175 in either Fig. 38 or 39. At the time of this opening impulse generator arm 88 is not on any contact. Hence, corresponding push button holding magnets 8 are de-energized and all push button parts returned to normal.

By referring to Fig. 40, it will be found that the combined up and down push button equipment for each intermediate floor for a sixteen elevator installation as described, requires six return conductors. This compares with thirty-four return conductors required by any system using an individual return for each up and down button and each up and down signal light over each elevator doorway. My system also provides convenience, freedom from confusion, a responsive feature, visual and audible directional and identifying signals, and "Remote" signals.

I will now describe the connections to the terminal special cross-arms and related parts, when such are required, for illustrative purposes speaking of these as applying to the upper terminal of a sixty floor installation. If a button has been pressed at the sixtieth floor, the carrier of the first elevator approaching the sixtieth floor effectively contacts with the corresponding cross-arm. This, together with its contact pivot block, is similar to any intermediate floor up cross-arm 70 and block 74, and the signals function at the sixtieth floor and in the serving car. As the car gets close to the sixtieth floor, the car visual signal is darkened by the reversal of carrier reversing switch 145. The visual signals at the floor remain illuminated, as their darkening is controlled by the return of cross-arm 70. Re-

ferring to Fig. 40, conductor 179 is connected to contacts 170 of the down push button for the two banks of elevators at the fifty-ninth floor, conductor 180 is similarly connected at the fifty-eighth floor, and conductor 181 is similarly connected at the fifty-seventh floor. Conductor 182 is connected to polarized magnet 8 corresponding with the down button for the left bank of elevators at all three of these floors, and conductor 183 is similarly connected for the right bank. All other connections at these three floors for the down push buttons and their related parts are the same as for any intermediate floor. Conductors 179, 180 and 181 are normally connected together and to conductor 184 by armature 185 of electro-magnet 168. If the left bank down push button on the fifty-ninth floor is pressed, its local connections being similar to the connections of a down push button at any intermediate floor, circuit is established from positive line, through its corresponding source of light 20, magnet 8, contact 169, contact 170, conductor 179, momentary opening switch 172, contact 186, contact 187 and corresponding magnet 156 to negative line. As has been described with respect to an intermediate landing, circuit is automatically established through magnet 8 of the down button of the right bank, and both buttons are illuminated. Similar results would follow in similar manner, the pressure of a down push button at the fifty-eighth floor, the connection between push button and controller being through conductor 180, and at the fifty-seventh floor through conductor 181, except that in this last case the circuit continues from conductor 181 through momentary opening switches 171 and 172 direct to corresponding magnet 156 and thence to negative line. It will be observed that in each case magnet 156 has taken the place of resistance 173 of an intermediate push button circuit. Immediately the serving elevator starts down from the sixtieth floor, corresponding up cross-arm 70 is returned through the action of special arm 150 on shaft 111 as shown in Figs. 33, 34 and 35, and the visual signals at the sixtieth floor are darkened. As screw 96 turns, it turns friction nut 97, which reverses reversing switch 94, moves up bell crank 76 out of contacting position and down bell crank 77 into contacting position, and the latter contacts with down cross-arm 151. If the down push button at the fifty-ninth, the fifty-eighth, or the fifty-seventh floor has been pressed, or the button at any one or two or at all of these has been pressed, cross-arm 151 will be sensitized. This is due to the connecting together of the several push button circuits through bar 185, which also joins them through conductor 184 and contact 143 and 142 and contact 139 to cross-arms 151. The cross-arm movement resulting from the energizing of each of the three magnets 156 has been described. The carrier solenoid jumps up, rotates its corresponding cross-arm 151, rotates shaft 160 in Figs. 43 and 44 and with it any one, two or all three 84 and 159, depending upon which buttons have been pressed, and 158 secured to shaft 160 is locked. The carrier plunger descends and transmits its signal impulses to the corresponding push button box or boxes. As to the manner of this transmission, if the serving elevator is in the left bank, left cross-arm 151 has been rotated and right 151 has been rendered dead by the separating of related contacts 142 and 143. In rotating, left 151 has transferred its connection to contact 140 and conductor 182, which is con- 75

nected to corresponding polarized magnets 9 at all three of the floors. Any of these whose permanently connected contact 174 is also in contact with corresponding contacts 170 and 169 will be energized by the generated impulses. Any not so connected will not be energized. Similarly, if the serving elevator is in the right bank, left 151 is rendered dead and through conductor 183, any effectively connected polarized magnet in a right hand push button box is energized. The signaling is the same as with intermediate floor push button boxes.

In rotating 151, contact 189 was connected to contact 190. A circuit was thus established from positive line, through contact 190, contact 189, and magnet 168, to negative line, moving bar 185 out of contacting position with respect to conductors 179, 180, 181 and 184 before the impulses were transmitted, and polarized magnets whose related buttons had not been pressed were thus not affected by the impulses. Simultaneously, armature mounted bar 185 moved contacts 186 out of connection with contacts 187 and into connection with contacts 188. 186 connected with 188 before leaving 187. This latter action substituted resistances 191 for magnets 156 in the push button circuits pertaining to cross-arms 154 and 155, for the purpose of de-energizing these magnets before the return of their respective-cross arms. If cross-arm 154 has been rotated, it is returned by arm 116, Fig. 16, after the landing has been served, and related switch 172 is momentarily opened, returning corresponding push button box parts to normal. The same applies to cross-arms 155 and 151 and their related parts. It was not necessary to substitute resistance for magnet 156 related to cross-arm 151, as this cross-arm is not mechanically connected to magnet 156, being rotated by its contact fingers 72.

Should it be desired to have more than one push button box at a floor related to the same bank of elevators, I make a slight change in the arrangement. For instance, assume that there are six elevators in the bank and that two push button boxes are desired; one between the second and third elevators and one between the fourth and fifth elevators. Then, the elevator at the left hand end of the bank would be the second elevator to the left of the first of the above push button boxes, but the fourth to the left of the second of the above push button boxes. I arrange that the impulse generator on the corresponding carrier shall send four impulses. On the first of the above two push button boxes, I close the third and fourth illuminable spaces 1 to the left of the push button, with decorative inserts, and change the notched outline of light baffle 7 on that side so that the opaque body of the baffle is deeper by the depth of two notches for each of the first two positions on that side. The first two impulses move the baffle as usual, but do not open any light ports on that side. The third impulse opens the light port for the space 1 next to the button and the fourth impulse opens the port for the second space from the button. The baffle on that side of the button in the second push button box has not been changed. The four impulses therefore indicate that the serving elevator is the fourth elevator to the left of the second push button box and that it is the second elevator to the left of the first push button box. To provide for the correct number of hammer strokes for the audible signal in the first push button box, I actuate this hammer by means of an electro-

magnet, instead of directly from shaft 34. The contacting for this electromagnet is effected through the movement of segment hub extension 53 and stationary contacts corresponding with its position on the third and fourth impulses. The details of this contacting are shown in Fig. 53 referred to in a later description of audible signals or announcements by reproduction of human speech instead of by hammer strokes. By corresponding suitable changes I can therefore arrange for any desired disposition of push button boxes.

In Fig. 9, I showed the provisions for two separate indications at illuminable "Remote" space 2 and in Fig. 51 I show a wiring diagram for such arrangement. It will be evident that I can also effect the illumining of space 2 through the medium of contacting effected by the movement of segment hub extension 53, in response to the final impulse of any series, should conditions require such contacting.

In Fig. 11, I indicate contact 86 or 87, mounted on the carrier, as a means for effecting a single contact with guide cam 83. In Figs. 47, 48 and 49, I show three views of this contact elaborated into a switch mechanism for opening or closing a multiplicity of electric circuits.

In Fig. 40 I show visual signal 176 and audible signal 177 in the car connected to function simultaneously, and have mentioned that operators sometimes run by signalled landings. This may be due to inattention, in which case the combination of an audible with a visual signal in the car is of assistance. However, its occurrence is largely due to the fact that an operator has been receiving his signal when the car is only something less than one floor away from the floor at which he is to stop. The increased elevator speed which has been recently sanctioned will accentuate the difficulty attached to stopping within this limited space. In Fig. 50 I have shown contact 86 or 87 approaching a cam 83. On first touching cam 83, audible signal in the car 177 sounds; later, visual signal 176 is illuminated. The length of the second contacting level of the moving contact is less than that corresponding with the height of one floor. However, the total length of the moving contact is considerably greater than the vertical distance between two floors. The result is that the operator receives two separate signals, one audible and one visual, with a time element between, and has a longer time in which to prepare for his stop. If two consecutive landings have been signalled, the fact that the length of the traveling contact is greater than the distance between the two consecutive aligned cams 83 causes no confusion, as the toe of the traveling contact is raised out of contacting position for the second cam until the first encountered floor has been served, and the audible signal is sounded for the second encountered floor before the car can attain full speed after serving the first. Fig. 51 has been previously described as pertaining to two "Remote" locations.

In describing wiring diagrams, I have spoken of positive and negative line, indicating a direct current supply. By the use of proper magnets, I can employ alternating current, but, instead of one polarized magnet, I then employ two separate electromagnets for functioning the segments in the push button box, with corresponding increase in the number of connecting conductors. I also employ two separate magnets, in conjunction with a direct current circuit, to meet

any condition to which the use of a single polarized magnet is not suited.

I have described the audible signals at floors by hammer strokes and will now describe the manner in which I provide audible signals or announcements at floors by reproduction of human speech.

Loud speakers are provided adjacent to the push buttons, in conjunction with phonograph records corresponding with each car. With selective switching between a reproducer on the phonograph and the proper loud speaker, the announcement is made.

Fig. 53 shows one of the reproducers 273 with its horn facing a transmitter 300. Each combination of horn and transmitter is soundproof from each other such combination. One side of individual battery 301 is connected to transmitter 300 and the other side to common wire 302 extending to the bottom of the hoistway. Transmitter 300 is also connected through switch 303 to individual conductor 304 extending to the bottom of the hoistway. 28 is the segment in the landing push button box controlling the movement of the light baffle to the right of the up push button. 53 is its hub extension and 51 is the corresponding suspension, both of which latter are properly insulated. 305 is a dashpot mechanically linked to suspension 51 for the purpose of slightly delaying its downward movement without interfering with its upper movement. Stationary contacts 306 have been added in the path of hub extension 53. The third contact 306 from the top is shown connected to conductor 304. In addition to the contacts previously described, normally separated contacts 307 and 308 are shown in a position to be electrically connected when the up push button is pressed. 298 and 299 are the loud speaker and horn corresponding with the up push button. 90, 88 and 91 are parts of the impulse generator on the carrier 58 corresponding with the third elevator to the right of the push button box, as described in Fig. 11. 288 is the electromagnet which moves the needle of the corresponding reproducer 273 in Fig. 53 into contact with its sound track on a constantly rotating phonograph record during the period of its announcement. 163 is the corresponding coil of the circuit breaker shown in Fig. 40. For an elevator to the left of the push button box, this coil would be 162. As has been previously described, when push button 10 is pressed and the third elevator to the right is the serving elevator, hub extension 53 will eventually be moved and come to rest at a position corresponding with that of the contact 306 connected to conductor 304. In bringing this about, arm 88 of the impulse generator on its downward stroke would have successively connected with three contacts 91 and would at the last have momentarily connected with contact 102, connecting it (in this instance) with coil 163. A circuit is momentarily established from negative line, through coil 163, arm 90, arm 88, contact 102 and magnet 288 to positive line, and the needle of corresponding reproducer 273 contacts with its corresponding sound track on a phonograph disc and the recorded announcement is reproduced. The circuit by which it is transmitted from corresponding transmitter 300 to corresponding loud speaker 298 may be traced from positive battery 301, through transmitter 300, switch 303, conductor 304, connected contact 306, extension 53, suspension 51, connected contacts 307 and 308, loud speaker 298 and com-

mon wire 302 to negative battery. None but the correct announcement can be transmitted to loud speaker 298 as the first impulse from the impulse generator separates 53 from 51, and they do not again electrically connect until 53 has come to rest on the contact 306 corresponding with the total number of impulses generated. Before the return of 51 and 53 to normal, the loud speaker circuit is opened at contacts 307 and 308. Switch 303 was introduced to show that the battery and individual conductor of any transmitter may be arranged to be transferred at will to another transmitter for the transmission of a different disc record, or for a special announcement directly by the human voice, or for any other sound transmittal. The other three transmitters are shown connected to their individual batteries and conductors and are supposedly disposed as described in conjunction with their respective reproducers.

The recorded announcement in any sound track pertains to one elevator only. The recorded announcement in any sound track pertains to but one direction of elevator travel. This announcement is automatically reproduced at any floor. It is always a complete announcement. For the sixteen elevator, sixty floor installation there would be four turntables. In principle, but one mould would be required to produce the disc records in quantity, as the records for one of the banks of elevators duplicate those for the other bank, and for the total of sixteen different sound tracks required, the reproducers surrounding one turntable could be aligned with eight of these and the reproducers surrounding another turntable could be aligned with the other set of eight. The wear of discs and needles is confined to the brief contacts while respective announcements are being transmitted.

With the loud speakers and selective system available, the way is also opened for locating individuals, transmitting fire- and burglary-alarm, making announcements and providing entertainment at one or many locations.

I will point out that while I have mentioned and shown positive and negative line, which would indicate a direct current supply, I function electric globes and non-inductive resistances quite as readily from an alternating current supply, and utilize appropriately constructed electro-magnetic units, but I cannot employ the polarized magnets on an alternating current circuit. When the current supply is alternating, or if for any other reason the polarized magnets are unsuitable, I displace them with two electro-magnets. This necessitates two return conductors instead of the one required by the polarized magnet.

For non-business hours, when elevators are not operating on schedule, it is customary to so change the system of calling from those floors above the ground floor, that the pressure of a button at one of these upper floors energizes an audible signal within hearing of an operator or watchman normally stationed at the ground floor, who then operates an elevator to answer the call. With some arrangements for this purpose, the audible signal at the ground floor has been accompanied by no further indication, and if, for instance, the down button at the third floor was pressed, it was necessary for the operator to run his car the entire height of the building and then run down, and it was not until he reached the third floor on the down trip that he learned the location of the intending passenger.

ger. In the meanwhile, the intending passenger had no means of knowing that his call had been registered. After waiting awhile, he was quite likely to again press the button, which again 5 sounded the audible signal, leaving the operator in doubt as to whether it was necessary for him to again run the elevator the entire height of the building to answer the call of some other intending passenger. Other arrangements have included some form of annunciator in a car. Still 10 other arrangements, particularly for buildings having a large number of elevators, have one or more elevators particularly assigned to night service, and when a button related to a bank of 15 elevators not so assigned, is pressed, a space is illuminated in a frame entirely separated from the button, referring the intending passenger to the night elevators, but in a large building these are not always easy to locate. The building may 20 cover an entire city block.

Fig. 55 shows the manner in which I provide for night service in connection with my system, when the cars are manually controlled. 10 and 10 represent the up and the down buttons at 25 any of the floors, with their equipment and connections as have been previously described. When any floor button is pressed, it is immediately illuminated, informing the intending passenger that his call has been registered. 497 is the 30 conductor leading to left hand guide 60. 498 is an electric globe in an annunciator case in the car. There is one up and one down globe corresponding with the annunciator indications for each floor. 499 is an audible signal. When the 35 switch arm shown is disconnected from conductor 497 and is connected to the annunciator circuit as shown, the pressure of any floor button energizes its holding magnet, its corresponding bulb in the annunciator case and the audible signal 40 in the car. When the landing is served, pressure of general return handle 500, or of individual button 350, returns to normal.

While I have previously omitted to so specifically state, when occasion requires I provide more 45 than one source of light for illuminating the push button and spaces in a landing push button box. If a particularly strong light is required, or for other reasons, I supply a separate source of light corresponding with each. When the same controller cross-arm spans carriers corresponding 50 both with express elevators and local elevators, I omit contact fingers 72 from the express section of those cross-arms corresponding with floors which the express elevators do not serve, 55 or insulate a corresponding section of the left hand guide 60 of each express elevator to prevent energizing of solenoid 62 on the carrier of said express elevator while said carrier is in that part of the carrier's travel which might cause interference with local elevator calls. When the carrier corresponding with an express elevator and the carrier corresponding with a local elevator of two elevators operating in the same hoistway, travel in the same guides, I so arrange a cam and 60 contact or a separate contacting strip and contact that the solenoid 62 of the express carrier is connected to left hand guide 60 or to negative line only during such part of its travel as calls for effective cross-arm contacting. With regard to 65 department store use of the equipment for announcements by reproduction of human speech, I automatically contact a loud speaker in each elevator car to announce the departments on each floor as the corresponding elevator approaches the corresponding floor.

I have described my system as related to a multiplicity of elevators but I do not wish to be limited to such relation.

I claim:

1. In an elevator signaling system including in combination, centralized push buttons and car designating signal means at each intermediate floor landing, said car designating signal means comprising an up and down signal lamp, windows situated at each side of the push buttons corresponding with the elevators at each side of said push buttons and adapted to be illuminated by said signal lamp, a light baffle normally maintained in a position to block out light from said windows, an electro-magnetically operated pawl and ratchet mechanism to shift said baffle a certain distance to illuminate all of the windows from the push button out to and including the particular window which designates the door to be served by an approaching elevator, and a controller to control the electrical impulses transmitted to said electro-magnet, said controller comprising a traveling solenoid having a movement corresponding to the movement of an elevator, an electrical connection between said solenoid and the push button, a mechanism co-operating with the plunger in said solenoid to actuate a contact-wiping member and contacts corresponding in number to an approaching car, over which said wiping member passes to complete an electrical circuit with the said electro-magnet and thereby send the required number of electrical impulses through same.

2. A controller for operating floor signals in an elevator signal control system comprising in combination a vertically movable solenoid member corresponding with each elevator, mechanism for moving same at the same relative speed as the moving elevators, guides to support said solenoid member, pairs of horizontally disposed cross-arms corresponding with each floor pivotally mounted in end supports, electrical contacts on each cross-arm corresponding with each elevator, a push button on each floor landing, electrically connected with its corresponding cross-arm to sensitize same, a contact wiper to energize said solenoid upon engagement with said cross-arm and means actuated by said solenoid, to rock said cross-arm and move its contacts out of the path of other contact wipers, and means for de-energizing the solenoid by the rocking movement of the cross-arm, a plunger within said solenoid which is moved upward abruptly when the solenoid is energized and means for retarding its downward movement, a contact arm actuated by the downward movement of the solenoid plunger and contacts engageable thereby electrically connected with the floor signals.

3. In an elevator signaling system including in combination, push buttons, means for illuminating same when pressed, signals to designate which door will next be served by an approaching elevator, said signals being arranged in close proximity to said push buttons, lighting means behind said signals and a baffle to normally exclude the light from same, an electro-magnetically operated mechanism for shifting said baffle to illuminate the signal which designates the door at which an approaching car will stop, and a controller mechanism corresponding with a serving elevator for controlling the electro-magnetically operated mechanism.

4. In an elevator signaling system including in combination up and down car signaling push buttons at each floor landing, car designating signals

arranged in close proximity to said push buttons, shutter members to normally conceal the car designating signals, stepped portions on said shutter members, an impulse generator associated with each elevator car and movable by the movement of its associated car, means co-operating with said landing push buttons to actuate the impulse generator corresponding with an approaching elevator and thereby shift its associated shutter member, whereby signals will be exposed in an order starting with the one nearest the push button and will continue in a step-by-step relation until the particular signal is reached which designates the car which will next serve that landing.

5. In an elevator signaling system including in combination centralized landing push buttons and car designating signal means at each intermediate floor landing, said car designating signal means comprising an up and down signal lamp, windows situated at each side of the push buttons corresponding with the elevators at each side of said push buttons, baffles normally maintained in a position to block out said windows, an impulse generator associated with each elevator car and movable by the movement of its associated car, means co-operating with said landing push buttons to actuate the impulse generator corresponding with an approaching elevator and thereby shift its associated baffle to expose the windows starting from one push button, out to and including the particular window which designates the door to be served by the approaching elevator.

6. In an elevator signaling system including in combination centralized push buttons and car designating signal means at each intermediate floor landing, said car designating signal means comprising an up and down signal lamp, windows situated at each side of the push buttons corresponding with the elevators at each side of said push buttons and adapted to be illuminated by said signal lamps, light baffles normally maintained in a position to block out light from said windows, an impulse generator associated with each elevator car and movable by the movement of its associated car, means co-operating with said landing push buttons to actuate the impulse generator corresponding with an approaching elevator and thereby shift its associated baffle, whereby signals will be exposed in an order starting with the one nearest the push button and will continue until the particular window is reached which designates the car which will next serve that landing.

7. In a signal system for a multiplicity of elevator cars, impulse actuated signals for each floor including an electro-magnetically actuated shutter adapted to be actuated intermittently to expose a signal upon each movement thereof, an impulse generator associated with each car and movable by the movement of its associated car including an electro-magnetically actuated member adapted to wipe across a plurality of contacts to complete an electrical circuit to the shutter operating electro-magnet and thereby provide an electrical impulse upon engaging each contact, and means for actuating an impulse generator associated with a car which will next serve a floor from which a service call has been made to thereby operate the floor signals.

8. In a signal control system for a multiplicity of elevator cars, call registering members and signals at each landing, a controller having selector contact members associated with the call

registering means and adapted to be sensitized by an associated call registering member, means associated with each car and movable thereby in the path of and in contact relation with said selector contact members and a reacting electro-magnetically operated device including an intermittently operated circuit closing means connecting said landing signals with said latter means to effect the operation of the floor signals after engagement is made with a sensitized selector contact member, and means to isolate the sensitized selector member after contact is made therewith.

9. In a signal control system for a multiplicity of elevators, the combination with floor signals and push buttons at each floor landing of a controller including cross-bars grouped in pairs and representing the up and down direction of car travel of a plurality of cars and adapted to be sensitized by their related push buttons, electro-magnetically operated mechanism associated with each car and movable by the movement of its associated car, means movable with said electro-magnetically operated mechanism adapted to move over each of said cross-bars and energize said electro-magnetically operated mechanism when engagement is made with a sensitized cross-bar, and means actuated by said energized electro-magnetically operated mechanism to control said signals.

10. In a signal control system for a multiplicity of elevators, the combination with floor signals and push buttons at each floor landing, of a controller including horizontally disposed cross-arms co-operating with each push button and adapted to be sensitized by the pressing of a push button, a carrier movable by the movement of the car, contact members on said carrier adapted to contact with each of said cross-arms, electro-magnetically controlled mechanism associated with each elevator car and located on said carrier which is adapted to be actuated when a carrier contact member contacts with a sensitized cross-arm, and means co-operating with said electro-magnetically controlled mechanism to operate the floor signals.

11. In a signal control system for a multiplicity of elevators, the combination with floor signals and push buttons at each floor landing, of a controller including horizontally disposed cross-arms co-operating with each push button and adapted to be sensitized thereby, a carrier movable by the movement of the car, vertically movable contact members on said carriers adapted to contact with each of said cross-arms, impulse generating mechanism supported by said carrier including a solenoid and plunger member adapted to be energized when a vertically movable contact member engages a sensitized cross-arm, means to de-energize said solenoid, and means operable on the return stroke of the solenoid plunger to energize a plurality of floor signal operating contacts.

12. In a signal control system for a plurality of elevators, the combination with floor signals and push buttons at each floor landing, of a controller including horizontally disposed cross-arms electrically connected with said push buttons, solenoid operated mechanism associated with each car, a carrier for said mechanism geared to the movement of its associated car, vertically movable contact members on said carrier movable over the horizontal cross-bars and adapted to complete a circuit with the solenoid when contact is made with any cross-arms which have

been sensitized by the pressing of associated push buttons, means actuated by the upward thrust of the solenoid plunger to move the sensitized cross-arm out of the path of other vertically movable contact members, and means actuated by the downward movement of the plunger to actuate the floor signals.

13. In a floor signal system for a multiplicity of elevator cars, impulse actuated signals at each floor, contacting members for each floor common to said elevator cars, push button actuated means for sensitizing any one of said common contacting members, an impulse generator associated with each car and movable by the movement of its associated car, means associated with each impulse generator adapted to wipe over said common contacting members and complete a circuit and energize the impulse generator when said wiper engages the sensitized contacting member, means to move said sensitized contacting member out of the path of other wiping means after said impulse generator is energized, and means for completing a circuit between the impulse generator and the floor signals.

14. In a system for controlling car signals in a multiplicity of elevator cars, contacting members for each floor common to said elevator cars, push button actuated means for sensitizing any one of said common contacting members, a reacting magnet associated with each car and movable by the movement of its associated car, means associated with each magnet to wipe over said common contacting members and complete a circuit to energize said reacting magnet when said wiping means engages the sensitized contacting member, means to move said sensitized contacting member out of the path of other wiping means when said magnet is energized, signals within each car, means actuated by the energized magnet to prepare a car signal circuit, and means movable with said reacting magnet to complete the car signal circuit.

15. In a signal and control system for a multiplicity of elevators, including up and down signal lamps at each landing, push buttons at each landing, a holding magnet for each push button, windows adjacent to said push buttons, shutters associated with said windows, polarized magnets to actuate said shutters, a controller including a contact arm associated with each push button, a movable member associated with each elevator and movable by the movement of its associated elevator, a contact wiper and a solenoid on said movable member, a resistance, an electric circuit completed through said holding magnet and resistance upon the pressure of a push button and adapted to sensitize said contact arm, another electric circuit completed to said solenoid by the wiping action of said contact wiper over said sensitized contact arm, a plunger actuated by said solenoid, means co-operating with said plunger on its initial stroke to move said contact arm to de-energize said solenoid and set up a circuit relation with a polarized magnet, and means co-operating with said plunger on its return stroke to complete the circuit to the polarized magnet and thereby operate the shutters and signals.

16. In a signal system for a multiplicity of elevator cars, floor signals including windows located to the right and left of push buttons at each floor, shutters to obstruct the passage of light therethrough, electro-magnetic means co-operating with each shutter, and an impulse generator associated with each car and adapted to

move said shuter intermittently whereby a band of light is presented through the windows with the last illuminated window designating the car which will next serve the land.

17. In an elevator signaling system, one panel structure including up and down call registering push buttons, an electro-magnetically operated switch-closing means, said panel structure being arranged in one position with relation to a bank of elevators at a landing, means to energize said electro-magnetically operated switch when a car approaches a landing at which a call has been registered, another panel structure arranged at a position remote to the first named panel structure to designate another bank of elevators, and a remote position indicating signal within each panel, one of which signals is adapted to be illuminated by the switch-closing means in the other panel, and when illuminated will inform an intending passenger that the elevator which will next serve the landing will be had at that section where the other panel is located.

18. In an electrical controller, a multiplicity of movable members, a multiplicity of electrical contactors normally in the path of said movable members, means for sensitizing any of said electrical contactors, a contact wiper carried by each movable member and adapted to wipe across said contactors, a re-acting electro-magnet carried by each movable member and electrically connected with an associated contact wiper, whereby upon the engagement of a wiper with a sensitized contactor the electro-magnet becomes energized, means to move said sensitized contactor out of the path of all other contact wipers when said electro-magnet is energized, circuit controlling switch members, and means movable by the movement of said sensitized contactor to change the contact relation of said circuit controlling switch members, whereby said electro-magnet is de-energized and the sensitized contactor is de-sensitized.

19. In an electrical controller, a multiplicity of movable members, a multiplicity of electrical contactors normally in the path of said movable members, means for sensitizing any of said electrical contactors, a contact wiper associated with each movable member and adapted to wipe across said contactors, a solenoid having a plunger movable therein and adapted to be energized when an associated contact wiper engages a sensitized contactor, means actuated by the movement of the solenoid plunger to move said sensitized contactor out of the path of other contact wipers, circuit controlling switch members, means co-operating with said sensitized contactor when moved to change the contact relation of said circuit controlling switch members and thereby de-energize said electro-magnet, a remote signal means having a plurality of contacts electrically connected therewith and a contact arm arranged to be moved into electrical contact relation with said signal contacts to operate said remote signal means on the return movement of the solenoid plunger.

20. In a signal control system for a multiplicity of elevators, the combination with floor signals and push buttons at each floor landing, of a controller including circuit controlling members representing the up and down directions of car travel with respect to each floor and adapted to be sensitized by their related push buttons when pressed, electro-magnetically operated means representing an associated car and movable by said car to maintain the same relative position

- with respect to the car, and circuit closing means movable with said electro-magnetically operated means and adapted to engage a sensitized circuit controlling member to thereby energize said electro-magnetically operated means, and a second circuit closing means operable by said magnetically operated means when energized to operate such floor signals as are associated with the sensitized circuit controlling member.
21. In a signal control system for a multiplicity of elevator cars, the combination of floor signals and call registering means for each floor landing, contacting members normally common to all elevator cars but individual with reference to the call registering means, said contacting members being adapted to be sensitized by associated registering means, and a reacting electro-magnetically operated device associated with each car including one circuit closing means adapted to engage any sensitized contacting member to energize the electro-magnetically operated device, and a second circuit closing means operable by said electro-magnetically operated device to thereby effect the operation of the floor signals associated with said sensitized contacting members.
22. In a signal control system for a multiplicity of elevators, the combination of floor signals and push buttons at each floor landing, a controller including a contacting member co-operating with each push button and adapted to be sensitized thereby when pressed, a contact wiper co-operating with each elevator car and movable by the movement of the car, and electro-magnetically controlled mechanism associated with each elevator car and energized when the contact wiper engages a sensitized contacting member, and a circuit closing member operable upon energization of the magnetically controlled mechanism which is adapted to establish and actuate signal operating circuits.
23. An electrical circuit controlling means for use with an elevator system, including in combination, call registering means at each landing, contacting members normally common to all elevator cars but individual with reference to the call registering means, said contacting members having an electrical connection with the call registering means to sensitize same upon registering a call, a reacting electro-magnetically operated device associated with each car, means movable over each contact member to energize said device when engagement is made with any sensitized contacting member to thereby establish an electrical circuit, and other contacting members associated with the electro-magnetically operated device to close the established circuit.
24. In an electrical controller, a multiplicity of movable members having contact wipers thereon, a multiplicity of electrical contactors normally in the paths of said contact wipers, circuit closing means for sensitizing any of said electrical contactors, a reacting electro-magnet carried by each movable member and adapted to be energized when a contact wiper engages a sensitized contactor, means actuated by said energized magnet to move said sensitized contactor out of the paths of wipers on all other movable members, and means actuated by said sensitized contactor, when moved, to de-energize said electro-magnet and to de-sensitize said contactor.
25. In an electrical controller for controlling a circuit to a signal device, a multiplicity of movable members having contact wipers thereon, a multiplicity of electrical contactors normally in the paths of said contact wipers, circuit closing means for sensitizing any of said electrical contactors, a reacting electro-magnet carried by each movable member and adapted to be energized when a contact wiper engages a sensitized contactor, means actuated by said energized magnet to move said sensitized contactor out of the paths of wipers on all other movable members, means actuated by said sensitized contactor, when moved, to de-energize said electro-magnet and to de-sensitize said contactor member, and means actuated by said electro-magnet upon de-energization thereof to operate the selected signal device.

WILLIAM NOBLE DICKINSON.
